UNITED STATES PATENT OFFICE

GALE S. ROBINSON, OF SEATTLE, WASHINGTON

DESIGN FOR A CALCULATOR CASING

Application filed June 13, 1932. Serial No. 44,065. Term of patent 7 years.

To all whom it may concern:

Be it known that I, GALE S. ROBINSON, a citizen of the United States, residing at Seattle, in the county of King and State of Washington, have invented a new, original, and ornamental Design for a Calculator Casing, of which the following is a specification, reference being had to the accompanying drawing, forming a part thereof.

In the drawing Figure 1 is a perspective

view of a calculator casing embodying my design.

Fig. 2 is a top plan view of the same.

Fig. 3 is a front elevation of said calculator casing.

Fig. 4 is an end view of the same.

I claim:

The ornamental design for a calculator casing, as shown.

GALE S. ROBINSON.
